UNITED STATES PATENT OFFICE.

HENRY WATKINS O'DOWD, OF NEW YORK, N. Y.

WATER-HEATER.

SPECIFICATION forming part of Letters Patent No. 703,738, dated July 1, 1902.

Application filed October 26, 1901. Serial No. 80,138. (No model.)

To all whom it may concern:

Be it known that I, HENRY WATKINS O'DOWD, a citizen of the United States, and a resident of New York city, in the county of 5 Westchester and State of New York, have invented a certain new and useful Water-Heater, of which the following is a specification.

This invention relates to means for quickly 10 heating water with gas as a fuel. It has for its objects, first, such an arrangement of the heating-surfaces as shall secure contact of the heat with all its parts; second, a circulation of the water that will insure its distribution 15 upon all the heating-surfaces, and, third, means for giving ready access to the heating parts to facilitate their external cleaning. These objects are accomplished by the means herein set forth.

20 In the drawings accompanying this specification, in which like numerals refer to similar parts throughout the several views, Figure I shows the heater in elevation and in partial section. Fig. II is a plan of the water- 25 sections and their inclosing jackets through line *a*, Fig. I. Fig. III represents a section of the heater having its top cut away or as taken through line *b*, Fig. I. Fig. IV shows a cross-section of one of the heating-sections 30 cut through its center, as at line *c*, Fig. I. Fig. V is a cross-sectional view showing how the heater-sections are united. Fig. VI is a 35 sectional view of one of the heater-sections, showing the course of the water in passing through it. Fig. VII is a sectional view of the heater, showing how the jacketing may be lifted from the water-sections for the purposes of cleaning. Fig. VIII is a plan of the 40 burner-plate that sustains the burners and the jacketing.

The water-receptacles of my heater are composed of preferably cast-metal sections—such as iron, steel, brass, copper, aluminium—and I have found three sections sufficient for 45 ordinary use. These sections are made somewhat larger in diameter than in length, and the sides are made in the form of corrugations, as in Figs. II, III, IV, and I have adopted an odd number, as five. The tops and 50 bottoms of the sections are plain surfaces, except as to the elevation of the hubs in the

centers, as shown in Figs. II and V. The tops and bottoms are pierced and provided with connecting-tubes, as 18, and in number they correspond with the corrugations of the 55 sides. These tubes are preferably cast integral with the rest of the section. These tubes constitute passages for the heat.

In each section 4, midway between the top and bottom, a baffle-plate 21, Figs. III, IV, VI, 60 is cast so as to connect with and is also integral with the tubes. A top view of this plate is shown in Fig. III. It is shown in elevation in Fig. VI and in cross-section in Fig. IV. Each section is provided with central 65 hubs 15 15', the hub 15' on one section being threaded to enter a screw-thread cut within the hub 15 on another section, as shown in Fig. V; but these sections may be united by means of pipe-nipples. A hole 19 through 70 the smaller hub allows of the passage of the water from one section to another. In Fig. VI the arrows show the courses the water must take in passing through a section. The small passage-way 19, preferably of the same 75 area as the water-supply pipe, concentrates the water at the centers of the sections, and the baffle-plate 21 causes it to spread out around and against the heated tubes and sides 80 of the sections.

In mounting these sections they are preferably alternated as to the side corrugations and the tubes, as shown in Figs. I and II, so that as the heat rises through a tube it impinges against the bottom of a section and is 85 deflected from its course to find the next tube, thus making contact with both the bottoms and tops of each section. So as to the corrugations. The broken or uneven side surfaces divert the rapid vertical ascent of the 90 heat between the sections and their jacketing, causing it to touch all over the corrugated surfaces.

The water-pipe 14 is screwed into the top and bottom sections, as indicated in Fig. I, 95 the inlet being preferably the bottom pipe.

Below the bottom section at a suitable distance a plate 12, having a hub 13, is secured on the water-pipe 14 by clamping or by means of a set-screw, as at 16, Fig. I. A section of this plate is shown in Fig. VII and a plan in Fig. VIII.

The jacketing for the heater-sections, as shown in Figs. I and VII, consists of a base 5, provided with a rim 10 and a flange 9. Over the rim 10 a sheet-metal jacket 1 is secured, and upon the flange 9 a sheet-iron jacket 2. Inside of the jacket 2 is a lining of asbestos or other non-conductor of heat 3. Upon the tops of these sheet-metal jackets a top 6 is secured by means of flanges 8 and 7. The water-pipe 14 passes freely through an outlet in the apex of the top 6. The top is also provided with a pipe-collar 11, to which a pipe may be attached for carrying away the products of combustion.

The top, the jackets, and the base are all securely bound together and constitute the jacketing of the heater, and the base is adapted to rest upon the burner-plate 12, as shown in Fig. I. The entire jacketing may be lifted from the burner-plate, as indicated in Fig. VII, and may be elevated above the water-sections, the top water-pipe 14 being made long enough to admit of this being done. Thus access to the sections is made convenient, which is a valuable feature of this invention, as in order to maintain the efficiency of such heaters it is important that they be cleaned occasionally.

The gas-burner is shown at 16 in Figs. I, VII, and VIII. The conditions do not require a particular form of burner. An annular burner is here shown consisting of two hollow concentric rings encircling the water-pipe 14. They are shown partly in section in Fig. I. The inner ring is connected with the outer one by the tunnel 16", and gas is admitted to both through the supply-tube 16'. The rings are otherwise connected by the webs 22, which afford means for attaching the entire burner to the base 12. The base 5 is notched out, as at 20, to admit of its dropping over the supply-tube 16, as shown in Figs. I and VII. The burner-base is per-

forated, as at 17, for supplying air for combustion.

It will be seen by reference to Fig. I that the water-sections are wholly enveloped in the heat rising from the burner and that the alternating of the tubes and the corrugated sides of the sections exposes all the surfaces to a uniform exposure to the action of the heat.

Having described my invention, what I claim, and desire to secure by Letters Patent, is—

1. A water-heater section having corrugated sides as shown, tubes uniting the top and bottom corresponding in number with the corrugations and located concentrically therewith, a deflecting-plate midway between the bottom and top surfaces and united with the tubes in the manner shown, and a central waterway in the top and bottom with means for connecting one section with another, substantially as herein shown and described. 65

2. The combination in a water-heater of cast sections, central threaded parts for connecting the sections said parts being provided with water-passages, the sections having corrugated sides and tubes corresponding in number to the corrugations and placed concentrically therewith, a deflecting-plate centrally of the sections and uniting with the tubes, and the sections mounted to alternate the tubes and corrugations so that the tubes and corrugations of one section will have a staggered relation to those of the adjacent sections, substantially as herein set forth. 75

Signed at 447 West Fourteenth street, in the county of New York and State of New York, 80 this 16th day of October, A. D. 1901.

HENRY WATKINS O'DOWD.
